UNITED STATES PATENT OFFICE.

FERNANDO CASABLANCAS PLANELL, OF SABADELL, SPAIN.

SCOURING MACHINE FOR WASHING FABRICS OF WOOL AND THEIR MIXTURES.

Application filed April 16, 1926, Serial No. 102,508, and in Spain April 21, 1925.

My invention relates to machines for washing fabrics of wool and its mixtures, known as scourers, and has for its special object to ensure uniform distribution of the pressures exercised by the washing cylinders or rollers on the pieces to be washed, in case of more than two pieces in the direction of width of the machine being simultaneously washed.

10 The usual scouring machines comprise two cylinders or rollers, the lower one of which is mounted on bearings of fixed position, whilst the upper roller rests on the lower one and is mounted in swivel bearings which allow it to take up a certain inclination in its vertical plane. Between these two rollers are caused to pass twisted to the shape of a rope or "ribbon" the pieces of fabric to be washed. As long as only a single piece, or two pieces, one at the side of the other, are caused to pass through the machine, the top roller always presses properly on the pieces of fabric to be washed, and in the case of two pieces passing, the 15 pressure of the top roller is evenly distributed between the two, even if one of the two pieces should be of a greater thickness than the other or only thicker along a portion of its length. On the contrary, when it is desired to pass through the machine three or four pieces, side by side, the top cylinder or roller properly presses only on two of these pieces, whilst it presses on the remaining one or two in a faulty manner, so that the 20 pressure of the roller is no longer evenly distributed over all the pieces, with the result that the washing is faulty.

25 This invention consists substantially in dividing the top roller into two parts arranged in line with each other and each mounted in such a manner as to enable it to assume in its vertical plane the inclination required in order to exercise a proper pressure on the pieces. In this way, it is possible to pass under each of the two top rollers two pieces of fabric, and the roller will exercise a uniform pressure on both, in such a manner that four pieces can be washed in the machine with the same perfection as if only 30 two were being washed.

Two constructions of a scouring machine with the improvements forming the subject of this invention, are shown in the accompanying drawings.

55 Figure 1 shows diagrammatically the ar-

rangement of an ordinary machine for washing simultaneously two pieces.

Figure 2 shows, also diagrammatically, the arrangement of an ordinary machine for washing simultaneously four pieces. 60

Figure 3 shows, also diagrammatically, the arrangement of a machine for washing four pieces at the same time, built in accordance with this invention.

Figure 4 is a side elevation of a machine 65 built according to the invention.

Figure 5 is a horizontal section of this machine on line VIII—VIII of Figure 4 and

Figure 6 is a front elevation of the same 70 machine, with the vat or tank containing the washing water in section.

The normal or standard washing machine for two pieces in the direction of its width, 75 comprises, see Figure 1, chiefly two rollers, the bottom one 1 and the top roller 2. The former has the journals working in two bearings secured to the bed of the machine, and the second one, 2, has them working in two special journals, the construction of 80 which allows the roller to oscillate, its axis remaining in the vertical plane passing through the same. This figure shows, without requiring any further explanation, how even in the case of two pieces 41 and 42 of 85 unequal thickness, the pressure due to the weight of the roller 2, added to that which eventually could be exercised on its bearings, is distributed among the two pieces which come between the roller 2 and the roller 1, 90 but the pressure on the pieces never ceases at any moment as long as the rollers are not excessively worn out.

The standard machines for washing three or four pieces in the direction of width, see 95 Figure 2, do not show any material difference from the preceding one, except as regards the width of the rollers 1 and 2. It is shown in this figure that of the four pieces which are being washed: 41, 42, 43 and 44, in all the places where their thickness is not the same, two of them, for instance 41 and 43, have no pressure acting on them, and only 42 and 44 are exposed to pressure, the result of which is a faulty 100 washing.

Figure 3 shows the scouring machine for four pieces with the improvements according to this invention. The bottom roller 1 is supported, like in a standard machine, in 110

two bearings secured to the bed of the machine, whilst the top roller is divided in the centre and forms two rollers 2, 2 entirely independent of each other. Each of these 5 rollers 2 rests on the corresponding portion of the bottom roller 1, with interposition of the pieces of fabric to be washed, and to that end these rollers are mounted in such a manner that their spindle can oscillate or swing in the vertical plane so as to ensure that they shall always rest or press on the pieces of fabric. In this way is obtained a reliable distribution of the pressure 10 on the pieces to be washed, similarly to the 15 case of Figure 1, but with the advantage that four pieces can be washed at the same time in an absolutely perfect manner.

The method of mounting these top rollers 2 so as to ensure their properly pressing on 20 the pieces of fabric to be washed, may vary according to individual cases, and various arrangements could be preferably adopted: one arrangement consisting in mounting the spindle of each of the two rollers 2 on 25 brackets or supports arranged at one and the same side of the machine in such a manner as to enable the said spindle to assume the necessary inclinations.

In the construction shown in Figures 4 30 to 6, a bar 5 is disposed parallel to the spindle of the top rollers 2 and also a bar 5 parallel to the spindle of the top rollers 2 and secured to the bed of the machine by means 35 of brackets 4. The bar 5 is provided at its two ends with swivelling arms 30, which are caused to pass through the bracket 4 in order to obtain a greater length of work with small space. These arms 30 are constituted by two connected sleeves the axes 40 of which intersect each other at right angles, one of the sleeves carrying the adjustment with the fixed bar 5 and the other carrying the arm 31 with hinge-like movement. This arm 31 which forms a right angle, constitutes the hinge pin with the arm 30 at one 45 side, and a fixed journal with the sleeves 32 and 33 secured to the top roller 2 of the machine. To limit the play of the said swivels or hinges in the longitudinal direction, are used collars 34 and 35 secured respectively to the bar 5 and to the arm 31 by 50 means of pins or keys.

The cast iron sleeve 32 is secured to the roller 2 by means of wedges and hoops put on hot, but not shown in the drawings.

In order to limit the movement or play of the roller 2 in the longitudinal direction, on the arm 31 is shrunk hot a hoop or collar 36 and a flange 37, the sleeve 33 thus being 55 held imprisoned, this sleeve forms a separate part with 32 so as to enable the roller 2 to be put on and withdrawn, and the roller 2 is connected to it by means of screws. For the purpose of lubricating these sleeves, in the arm 31 is provided a central conduit

38, at the outer end of which can be mounted a sight feed or other lubricator if oil is used as lubricant, or other type of lubricator if grease is used. To prevent the excess of the lubricant from wetting the roller 2 70 and spoiling the goods to be washed, the sleeve 33 is extended outwards beyond the bed or frame of the machine and has at the outer end a flange or lug 40 which prevents the lubricant escaping between the sleeve 33 75 and the arm 31 from getting into the interior and forces it to drip beyond the bed of the machine. It may be seen that the plane of the belt 29 is entirely free from the guide mechanism, so that there is full liberty to 80 arrange the drive from the position that may be considered best.

The sleeve 32 could be made of the dimension required in order to ensure an increase in the weight of the roller 2, and therefore 85 an increase of pressure on the pieces to be washed, but in this case as well as in the case of an already existing roller, the weight can be increased, and the disturbing effect of the arm 30 and of the part 31 can be counteracted by means of suitably arranged balance 90 weights.

In fact, the collar 35 is provided with an arm 17 which supports a sliding weight 18, and the arm 31 is provided, towards the rear 95 part of the machine, with an extension 15 which in its turn carries a sliding weight 16. By suitably graduating the size and the position of these weights, the desired effect 100 may be obtained.

In spite of the guide mechanism being free from any important stresses owing to its being able to follow the movements of the roller 2, and for the purpose of reducing these stresses to a minimum, the upper roller 2 is arranged somewhat in front of the roller 1 in order that the tendency of the former to slide on the latter towards the front portion of the machine, should balance the strain which the bottom roller 1 produces on the top roller 2 when the machine is working in order to overcome the torque of the roller 2 which plays the part of a driven roller. This arrangement can be seen in Figure 4.

Moreover, to these machines with the improvement forming the subject of this invention are applicable any others that are generally applied to machines with an undivided top roller, such as knocking off motion for preventing the pieces from being damaged when they get entangled with each other, protective covers, and the like.

I claim:—

1. In a scouring machine for washing fabrics of wool and its mixtures, the combination of a lower roller over which pass the pieces of fabric to be washed, two upper rollers independent the one from the other and arranged the one in prolongation of the 120 125 130

other, these rollers pressing on the pieces of fabric which have to be washed.

2. In a scouring machine for washing fabrics of wool and its mixtures, a tank or receptacle, a roller arranged in the interior of this tank or receptacle and adapted to be given a rotary movement, two rollers arranged above this lower roller the one in prolongation of the other, said rollers adapted to receive therebetween the pieces of fabric to be washed with the fabric passing between the lower roller and the upper rollers, the said upper rollers being mounted in such a way that they are free to move in a vertical plane so as to press freely upon the pieces of fabric.

3. In a scouring machine for washing fabrics of wool and its mixtures, a lower roller revolving in bearings fixed to the frame of the machine, over which roller pass the pieces of fabric which have to be washed, two upper rollers running loose arranged the one in prolongation of the other, these upper rollers resting on the lower roller with the interposition of the pieces of fabric which have to be washed and the axles of these upper rollers being mounted in such a way that they can move freely in a vertical plane so that the upper rollers may press conveniently upon the fabrics whatever may be the thickness of the same.

4. In a scouring machine for washing fabrics of wool and its mixtures, a lower roller endowed with a rotary movement, two upper rollers arranged the one in prolongation of the other and which press upon the lower roller, the pieces of fabric to be washed pass-

ing between the lower roller and the upper rollers, the said upper rollers being mounted in such a way that they can move freely in a vertical plane and being provided with levers and weights so as to be able to increase or lessen the pressure which they exert upon the pieces of fabric to be washed.

5. In a scouring machine for washing fabrics of wool and its mixtures, a lower roller which revolves upon bearings fixed to the frame of the machine, two upper rollers running loose arranged one in prolongation of the other and which rest upon the lower roller, the pieces of fabric to be washed passing between the lower roller and the upper rollers, the said upper rollers being mounted in such a way that they can move freely in a vertical plane and with their axles situated forward of the vertical plane passing through the axis of the lower roller.

6. In a scouring machine for washing fabrics of wool and its mixtures, a lower roller which revolves upon the bearings fixed to the frame of the machine, two upper rollers arranged one in prolongation of the other which rest upon the lower roller, the pieces of fabric to be washed passing between the said lower roller and the said upper rollers and two arms mounted upon the frame of the machine, in such a way that they can move freely in a vertical plane, which arms are introduced into the interior of the said upper rollers, and serve as fixed axles upon which said upper rollers rotate.

In testimony whereof I have signed my name to this specification.

FERNANDO CASABLANCAS PLANELL.
